HAIR COMB DEVICE

Nate Gambino, Modesto, Calif.

Application May 7, 1946, Serial No. 667,857

4 Claims. (Cl. 132—11)

1

This invention relates to toilet articles and more particularly to hair combs.

A main object of the invention is to provide a novel and improved hair comb device which is provided with means for collecting the various deposits present in the hair such as loose dandruff, lint, dust, and the like, without clogging up the spaces between the comb teeth.

A further object of the invention is to provide an improved hair comb device of simple construction which is inexpensive to manufacture, said device including a collection chamber for foreign material in the hair, said chamber being very accessible for removing the collected material when the comb device is to be cleaned.

Further objects and advantages of the invention will become apparent from the following description and claims, and from the accompanying drawing, wherein—

Figure 1 is an elevational view of a comb device constructed in accordance with the present invention.

Figure 2 is an end view of the comb device of Figure 1.

Figure 3 is a transverse cross sectional view of the comb device of Figure 1.

Figure 4 is a top plan view of an end portion of the comb device of Figure 1 with the closure member thereof removed.

Figure 5 is a perspective view of a closure member employed with the comb device of Figure 1.

Referring to the drawing, the comb device comprises a body portion 11 consisting of an elongated hollow relatively flat upper portion 12 which is generally rectangular in cross-section, said upper portion having integrally formed therewith a plurality of depending comb teeth 13 extending along the entire length of portion 12 and evenly spaced with respect to each other along said length. As shown in Figures 2 and 3, the teeth 13 are small in transverse width as compared to the transverse width of the hollow upper portion 12 and are positioned at one side of said upper portion. The side wall of said upper portion adjacent the teeth 13 terminates a short distance above the plane of the bottom wall thereof, said bottom wall, designated at 14, terminating a short distance inwardly of the plane of said side wall. There is thus defined between the upper end portions of the adjacent teeth 13 an inclined opening 15 which leads into the interior of the hollow upper portion 12 of the comb. The forward edge of lower wall 14, indicated at 16, is so positioned that when the comb is drawn

2

through the hair (toward the right, if the comb is positioned as shown in Figure 2 and 3) the edge 16 between the upper portions of adjacent comb teeth acts as a scraping blade to scrape foreign material from the hair and to guide the scraped material into the hollow upper portion 12. Said hollow upper portion thus functions as a collection chamber for the dislodged foreign material.

10 The side walls of portion 12 are formed with a pair of longitudinal grooves 17, 17 and engaged in these grooves are the inturned flanges 18, 18 of a channel-shaped closure member 19 which normally overlies the open top end of hollow portion 12. When the interior of said hollow portion is to be cleaned, closure member 19 is removed by sliding it longitudinally in grooves 17, 17 to thereby disengage it from the body portion of the comb. After the collected foreign material has been cleaned out of hollow portion 12 the closure member 19 may be replaced by engaging the inturned flanges 18, 18 in grooves 17, 17 and sliding the closure member 19 back to overlying position with respect to the top of hollow portion 12.

20 The provision of the hollow receptacle 12 at the upper portion of the comb avoids the unsightly deposit of loose hair, fluff, dandruff, and the like, around the root portion of the comb teeth as occurs in conventional combs, inasmuch as in the comb of the present invention practically all dislodged material from the hair is forced through the inclined openings 15 into the collection chamber by the combing action, and the collecting action is aided by the scraping action of the horizontal edges 16 at the bottom of said openings.

25 While a specific embodiment of a dirt-collecting hair comb has been disclosed in the foregoing description, it will be understood that various modifications within the spirit of the invention may occur to those skilled in the art. Therefore it is intended that no limitations be placed on the invention other than as defined by the scope 30 of the appended claims.

What is claimed is:

35 1. A comb device comprising a hollow, substantially flat, elongated body member, a plurality of comb teeth depending from one side of said body member, said teeth being relatively small in transverse width compared to the transverse width of the body member, the side wall of the body member adjacent the teeth terminating a short distance above the plane of the bottom wall 40 45 50 55 of the body member and the bottom wall ter-

minating a short distance from the plane of said side wall to thereby define openings between the root portions of adjacent comb teeth, said openings being inclined upwardly with respect to the plane of the bottom wall.

2. A comb device, comprising a hollow elongated body including a front and a bottom wall lying in intersecting planes but terminating in spaced free edges, and a plurality of spaced comb teeth depending from said free edges of said side and bottom wall, whereby to provide diagonally downwardly and outwardly directed openings from the interior of said body between said teeth.

3. A comb device, comprising a hollow elongated body including a front and a bottom wall lying in intersecting planes but terminating in spaced free edges, and a plurality of spaced comb teeth depending from said free edges of said side and bottom wall, whereby to provide diagonally downwardly and outwardly directed openings from the interior of said body between said teeth, and a removable closure for said body.

4. A comb device, comprising a hollow elongated body including a front and a bottom wall lying in intersecting planes but terminating in spaced free edges, and a plurality of spaced comb teeth depending from said free edges of said side and bottom wall, whereby to provide diagonally downwardly and outwardly directed openings from the interior of said body between said teeth, said teeth having front edges lying substantially in the plane of said front wall.
